(57) **CLAIM**

The ornamental design for a vial, as shown and described.

DESCRIPTION

FIG. 1 is a perspective view of a first embodiment of the vial, in a closed state;

FIG. 2 is a perspective view of the vial of FIG. 1, in an opened state;

FIG. 3 is a top plan view of the vial of FIG. 1, in an opened state;

FIG. 4 is a bottom plan view of the vial of FIG. 1, in an opened state;

FIG. 5 is a right side elevation of the vial of FIG. 1, in an opened state;

FIG. 6 is a front elevation of the vial of FIG. 1, in an opened state;

FIG. 7 is a left side elevation of the vial of FIG. 1, in an opened state;

FIG. 8 is a rear elevation of the vial of FIG. 1, in an opened state;

FIG. 9 is a cross sectional view of the vial of FIG. 1, in a closed state;

FIG. 10 is a cross sectional view of the vial of FIG. 1, in an opened state;

FIG. 11 is a perspective view of a second embodiment of the vial, in an opened state;

FIG. 12 is a top plan view of the vial of FIG. 9, in an opened state;

FIG. 13 is a bottom plan view of the vial of FIG. 9, in an opened state;

FIG. 14 is a right side elevation of the vial of FIG. 9, in an opened state;

FIG. 15 is a front elevation of the vial of FIG. 9, in an opened state;

FIG. 16 is a left side elevation of the vial of FIG. 9, in an opened state; and,

FIG. 17 is a rear elevation of the vial of FIG. 9, in an opened state.

The broken lines in the drawing views are included for the purpose of illustrating portions of the vial that form no part of the claimed design

It is certified that error appears in the above-identified patent and that said Letters Patent is hereby corrected as shown below:

Title Page

At item DESCRIPTION, please delete the description of the figures in their entirety and substitute with the following:

FIG. 1 is a perspective view of a first embodiment of the vial, in a closed state;
FIG. 2 is a perspective view of the vial of FIG. 1, in an opened state;
FIG. 3 is a top plan view of the vial of FIG. 1, in an opened state;
FIG. 4 is a bottom plan view of the vial of FIG. 1, in an opened state;
FIG. 5 is a right side elevation of the vial of FIG. 1, in an opened state;
FIG. 6 is a front elevation of the vial of FIG. 1, in an opened state;
FIG. 7 is a left side elevation of the vial of FIG. 1, in an opened state;
FIG. 8 is a rear elevation of the vial of FIG. 1, in an opened state;
FIG. 9 is a cross sectional view of the vial of FIG. 1, in a closed state;
FIG. 10 is a cross sectional view of the vial of FIG. 1, in an opened state;
FIG. 11 is a perspective view of a second embodiment of the vial, in an opened state;
FIG. 12 is a top plan view of the vial of FIG. 11, in an opened state;
FIG. 13 is a bottom plan view of the vial of FIG. 11, in an opened state;
FIG. 14 is a right side elevation of the vial of FIG. 11, in an opened state;
FIG. 15 is a front elevation of the vial of FIG. 11, in an opened state;
FIG. 16 is a left side elevation of the vial of FIG. 11, in an opened state; and,
FIG. 17 is a rear elevation of the vial of FIG. 11, in an opened state.

Signed and Sealed this
Thirtieth Day of April, 2013

Teresa Stanek Rea
Acting Director of the United States Patent and Trademark Office
